UNITED STATES PATENT OFFICE.

CHESLEY T. SMALL, OF ST. LOUIS, MISSOURI, ASSIGNOR TO FIRST NATIONAL BANK IN
ST. LOUIS, OF ST. LOUIS, MISSOURI.

DUST-RETAINING DEVICE FOR CAN-FILLING MACHINES.

Application filed December 23, 1918. Serial No. 268,031.

To all whom it may concern:

Be it known that I, CHESLEY T. SMALL, a citizen of the United States of America, residing at the city of St. Louis, State of Missouri, United States of America, have invented a certain new and useful Dust-Retaining Device for Can-Filling Machines, of which the following is such a full, clear, and exact description as will enable any one skilled in the art to which it appertains to make and use the same, reference being had to the accompanying drawings, forming part of this specification.

My invention relates to a dust retaining device for can filling machine; and is more particularly adapted for use in connection with a machine, such as shown in my prior application Serial No. 184,990 filed August 8, 1917, in which a nozzle enters the can during the operation of filling and performs not only the function of a nozzle but also of a displacing member. My invention may, however, be used in connection with other forms of can filling machines.

In the accompanying drawing which illustrates one form of device made in accordance with my invention, together with a portion of the filling machine to which the same is applied, Fig. 1 is a side view partly in section, Fig. 2 is a view similar to Fig. 1, but showing the can into which the nozzle projects, Fig. 3 is a sectional view showing a different form of can and also showing a filling member or position in the nozzle, and Fig. 4 is a top plan view of the nozzle and filling member detached from the other parts.

5 represents a nozzle carrying member which is like that shown in my prior application above referred to. Secured in an opening 6 in the said member 5 by means of a reduced upper part 7 provided with threads is a nozzle 8. The outer wall of the nozzle is straight below the reduced portion 7 while the inner wall is slightly tapered as best shown in Fig. 3 so that the internal area of the nozzle is greater at its lower end, in order to facilitate the discharge of the contents of the nozzle into the can or other receptacle to be filled. In the drawings, I have shown the nozzle as cylindrical in form.

It will be understood, however, that the form of the nozzle may be varied to adapt it to a different form of can or other receptacle.

The lower end of the nozzle is provided with an outwardly projecting flange 9 and the nozzle is surrounded by a dust retaining member 10 the central portion of which is spaced a slight distance from the outer wall of the nozzle 8. This dust retaining member 10 is provided with an inturned lower edge 11 adapted to fit snugly around the nozzle 8 and make dust tight contact therewith. The upper edge 12 of the member 10 is flared outwardly so as to provide a contact surface for engagement with the upper edge of the can and also to make contact with the lower face of the nozzle carrying member 5. Surrounding the nozzle 8 is a coil spring 14 bearing at one end upon the inturned lower edge 11 of the member 10 and at the other against the lower face of the member 5. The object of this spring 14 is to normally hold the member 10 against the flange 9 as shown in Figs. 1 and 3 of the drawings.

When the member 10 is forced upwardly by the can 15 as shown in Fig. 2, this spring 14 lies in the space between the nozzle 8 and the body of the dust retaining member 10, as shown in said Fig. 2. The can 15 shown in Fig. 2 is provided at its upper end with an inturned edge 16 while the form of can 15 shown in Fig. 3 is provided with an out-turned upper edge 17. In either case, or in case the upper edge is straight without any turned over portion, the upper edge of the can contacts with the flared edge 12 of the member 10, preferably at a point near to the junction of this outwardly flared portion with the body of the member. The nozzle carrying member 5 preferably has secured to it a wear plate 18 which over laps the upper edge of the nozzle 8.

As has been previously stated, my invention is particularly adapted for use in connection with a machine in which the nozzle performs not only the function of introducing the material into the can or other receptacle to be filled, but also acts as a displacement member for displacing a given quantity of material. In order that the amount of material displaced may be varied

without changing the nozzle, I provide a filling member 20 adapted to fit snugly against one side of the inner wall of said nozzle 8. This filling member 20 is held in place by means of a screw 21 passing through a suitable opening in the wall of the nozzle 8. In order to prevent accumulation of material on the upper edge of this filling member 20, it is provided with an extension 22 passing through a wear plate 18 and terminating flush with the upper face thereof, as shown in Fig. 3.

It will be obvious that by providing a number of filling members 20 of different thicknesses, the amount of displacement secured by the nozzle can readily be varied.

The operation of my device will be evident. When the member 10 enters the can 15 it makes dust tight contact with the upper edge of said can and while the nozzle is moving into and out of the can dust tight contact is maintained between the inturned edge 11 of the member 10 and the outer straight wall of the nozzle 8 so that no 25 dust can escape from the can during the operation of filling the same. In can filling machines of the type to which my invention is applicable and which are adapted to fill the receptacle with powdered or granular 30 material the nozzle must have a free unobstructed central passage for the material and hence the material cannot be cut off at the bottom of the nozzle but must be cut off at some point above the top of the can, such 35 for instance as at the upper surface of the wear plate 18. Consequently provision must be made for the reception of such material as is contained in the nozzle above the top of the receptacle when the nozzle is 40 removed. In my construction the amount of displacement to compensate for such excess material may be varied to a considerable extent by varying the distance to which the nozzle 18 projects into the receptacle 15. In 45 this way the receptacle may be filled completely full of material, or as is sometimes desirable, it may be filled only partially. When the desired amount of variation cannot be secured by means of the displacement 50 of the nozzle alone, the filling block 20 is added or a filling block of different size substituted. In this way all the necessary variation in the amount of material fed to the

can which is met in practice may be secured without changing the nozzle 8 itself.

Having fully described my invention what I claim as new and desire to secure by Letters Patent of the United States is:

1. The combination with a nozzle carrying member, of a nozzle therefor adapted to project a substantial distance into the receptacle to be filled and provided at its lower end with a retaining projection, and a dust retaining member sliding on said nozzle and adapted to engage at a point intermediate of its length with the upper edge of the receptacle to be filled, said member having an outwardly extending flange arranged above said contact point, an inwardly extending flange arranged below the same, said latter flange cooperating with the projection on said nozzle to limit the downward movement of the member.

2. The combination with a nozzle carrying member, of a nozzle therefor adapted to project a substantial distance into the receptacle to be filled and provided at its lower end with a retaining projection, a dust retaining member sliding on said nozzle and adapted to engage at a point intermediate of its length with the upper edge of the receptacle to be filled, said member having an outwardly extending flange arranged above said contact point and an inwardly extending flange arranged below the same, said latter flange cooperating with the projection on said nozzle to limit the downward movement of the member and closing the lower end, the space between said nozzle and member forming a spring retaining recess, and a spring situated within said recess.

3. The combination with a nozzle carrying member, of a nozzle carried by said member and projecting below the same, a wear plate arranged above said nozzle carrying member and overlapping the upper edge of said nozzle, and a filling member removably secured to one side of the inner wall of said nozzle, said filling member being provided with a reduced projection extending through the opening in said wear plate.

In testimony whereof, I have hereunto set my hand and affixed my seal.

CHESLEY T. SMALL. [L. S.]
